INVENTOR,
Albert Wanner Jr.,
BY
John Stewart,
ATTORNEY.

UNITED STATES PATENT OFFICE.

ALBERT WANNER, JR., OF NEW YORK, N. Y.

CHAIR.

1,324,186.

Specification of Letters Patent.

Patented Dec. 9, 1919.

Application filed December 1, 1917, Serial No. 204,956. Renewed October 22, 1919. Serial No. 332,549.

To all whom it may concern:

Be it known that I, ALBERT WANNER, Jr., a citizen of the United States, residing at New York city, in the county of New York 5 and State of New York, have invented certain new and useful Improvements in Chairs, of which the following is a specification.

This invention relates particularly to back-and-back-leg structures for chairs of the class in which the independence of the back-proper as a part of the design of said structure is emphasized by giving the frame of such back-proper an open or endless form. In the improved back-and-back-leg structure 15 the open-form back-proper, preferably cut out of a plate of laminated sheet material, is set into a half-check formed at the front of an inclined elongated head or enlargement integral with the upper end of each back 20 leg, which projects above the seat, the back proper having its central portion preferably depending below the point where it is half-checked into the legs so that the same is subjected to the pressure of the lower-back of 25 the occupant, thus in a material measure offsetting the pressure of the occupant's back against the top of the back-proper and thereby preventing undue leverage being exerted on the joints between the legs and back- 30 proper.

While thus producing a strong and durable construction and one that lends itself to wide variations in design, particularly of the back-proper, I produce a back-and-back-leg structure that may be manufactured at the minimum expense of time, labor and materials.

In the accompanying drawings,

Figure 1 is a perspective view of a chair 40 embodying my improvement;

Fig. 2 is a fragmentary side elevation, showing mainly the back-and-back-leg structure and the seat; and

Fig. 3 is a rear elevation of the joint be- 45 tween the back-proper and a back-leg.

In the drawing, *a* designates the seat and *b* the front legs of a chair; *c* designates the back-legs which are secured to the back of the seat in any well-known manner, their 50 upper ends projecting well above the seat.

The upper end of each back-leg is formed at the front with a half-check *d*, to which more detailed reference will be made.

The back-proper *e* is preferably made of 55 layers of laminated material (as layers of

wood having their grain crossed) cemented together, the plate of laminated material thus formed being suitably shaped to produce such back structure, as by being curved to conform to the back and by being provided with openings *f* and given a contour *g* which accord with some selected design; in the present instance the inner opening *f* is caned or upholstered.

The back-proper is assembled with the 65 legs *c* by being set into the half-checks *d* thereof and secured therein by screws and gluing or in any other suitable manner.

To provide for a more or less vertically elongated bearing of the back-proper against each leg the upper end of each leg is formed with an inclined elongated enlargement or head *h*, and the half-check *d* is formed in this enlargement or head longitudinally thereof; the two enlargements or heads converge downwardly. The design of the back-proper is subordinated to the joint to be effected between it and the upper end of each leg to the extent of producing the long up and down bearing of the back-proper on the 80 leg, but otherwise the design may be treated with entire freedom. In the present case, the lower part of the back-proper is oval-shaped, and the half-checks *d* are so shaped that they will conform thereto with the object of producing a flat face to face contact between the back face of the back-proper and the forwardly facing surface *d'* of each half-check and also between downwardly converging portions of the marginal face of 90 the back-proper and the downwardly converging inwardly facing surfaces *d''* of the half-checks.

Further, in the preferred construction, the lowermost middle part of the back-proper 95 extends below the joints formed between the same and the back-legs at the half-checks in the latter, so that the lower back of the occupant offsets the pressure which the upper part of the occupant's back exerts against 100 the top of the back-proper; this reduces considerably the leverage which would otherwise be exerted by the back-proper, with the tendency to break down the joint between the same and the back legs.

Having thus fully described my invention, what I claim as new and desire to secure by Letters Patent is:—

In a chair, the combination, with a seat and front legs attached thereto, of a back- 110

proper, and back-legs attached to the seat and projecting at their upper ends above the same and each having an elongated integral head at its upper end and a half-check 5 formed in the front of such head longitudinally thereof and having an inwardly facing surface and a forwardly facing surface, said

heads and their half-checks converging downwardly, and the back-proper being secured in the half-checks and bearing against 10 each forwardly and inwardly facing surface thereof.

In testimony whereof I affix my signature.

ALBERT WANNER, JR.
